PAPERMAKING MACHINE FLOW BOX

Everett W. Clem, Shrewsbury, Mass., assignor to
 Rice Barton Corporation, Worcester, Mass., a
 corporation of Massachusetts

Application March 3, 1947, Serial No. 732,011

1 Claim. (Cl. 92—44)

1

The present invention relates to the manufacture of paper and to the apparatus used in the manufacture of paper. More specifically, the present invention relates to a Fourdrinier type of paper making machine and means which may be applied to such a machine for effecting an improved method of manufacturing paper.

In paper making machines of the Fourdrinier type there is provided a large tank or flow box into which the pulp slurry is pumped at 1 to 3 percent concentration of pulp. From this flow box the pulp slurry passes over an apron board which is substantially the same width as the wire of the machine. By wire is meant the long endless wire belting upon which a pulp web is formed as the wire is advanced. The pulp slurry passes over this apron board from the flow box to be deposited on the endless wire, moving forward, on which it is spread evenly by a spreader or slice, and thus a continuous web or sheet, approximately the width of the wire, is gradually formed. Thence the web passes to the dry end of the machine which has a series of press rolls which remove water and consolidate the web. The web then passes to a number of steam heated cylinders to dry it into paper and to a further number of rollers to calender this paper. As above outlined these are the general steps in manufacturing machine-made paper by the Fourdrinier process.

In thus making paper in this manner one of the defects which has always existed is that it was practically impossible to maintain a homogeneous mixture of the pulp material within the water. For example, as the pulp slurry is pumped into the flow box, portions of the pulp will tend to coagulate in balls thus to prevent an even distribution of the pulp within the water solution. Whenever this pulp coagulation occurs, the resulting balls of pulp will pass to the endless wire of the machine and as the slice mechanism cannot adequately break up these pulp concentrations or balls, the paper sheet will be malformed.

In the past various mechanical devices have been provided within the flow box for agitating the pulp slurry in an effort to obtain an even distribution of the pulp within the water solution. However, none of these mechanical contrivances have been successful in breaking up the pulp concentrations to any appreciable degree.

Also, in the past various means have been devised for imparting vibratory motion to the endless wire in an attempt to redistribute the pulp fibers upon the wire so that a homogeneous dis-

2

tribution of the pulp fibers upon the wire will be effected. Such means have never adequately overcome the defects in product, noted above, for the reason that once the pulp has been placed upon the wire the water is drawn off the same and as a consequence any redistribution of the pulp fibres without the benefit of the water solution is next to impossible.

It is, therefore, a primary object of the present invention to provide a novel method of preparing a pulp slurry whereby the same may be deposited in a homogeneous manner upon an endless wire of the Fourdrinier type of paper making machine.

15 A more specific object of the present invention is to provide means for effecting an even distribution of pulp fibers within a water solution as the solution passes through a Fourdrinier flow box.

20 In accordance with the present invention a homogeneous dispersion of pulp fibers within a water solution is effected by passing compressional waves through the pulp slurry as the same passes through a Fourdrinier flow box. By so subjecting the slurry to compressional waves as the slurry passes through a flow box it has been found that the characteristic laminar flow of the liquid is broken up with the result that the pulp fibers will no longer concentrate in balls at the various side portions of the flow box. Also these compressional waves have been found to break up any pulp vortices that would otherwise produce balls of pulp fibers. A still further beneficial effect produced by these compressional waves is that the pulp fibers are rendered more buoyant for the reason that a portion of the water which is normally entrapped in the fibers is removed by the force of the waves against the individual fibers. Being more buoyant the pulp fibers tend to disperse more uniformly through the water solution. Therefore, by so subjecting the pulp slurry to these compressional waves it has been found that a more uniform pulp web can be formed on the endless wire of a Fourdrinier machine.

45 The invention will best be understood from the following description in connection with the accompanying drawings which illustrate the improved paper making machine and the method of operating the same.

Fig. 1 represents a top plan view of a Fourdrinier flow box in which the present invention is incorporated.

50 Fig. 2 represents a sectional view taken substantially along the line 2—2 of Fig. 1.

Fig. 3 represents an enlarged sectional view of an electrical vibratory mechanism.

Fig. 4 is a wiring diagram representing the electrical means whereby the vibratory means disclosed in Fig. 3 is energized.

Fig. 5 represents an enlarged sectional view of a pneumatic vibratory means.

Fig. 6 is a diagrammatic illustration showing the various steps required in the manufacturing of paper by the Fourdrinier process.

Fig. 7 represents a fragmentary top plan view of a Fourdrinier flow box illustrating the manner in which the pulp fibers separate out from the slurry thereby to form pulp fiber balls.

Fig. 8 represents a fragmentary vertical sectional view of a Fourdrinier flow box illustrating the manner in which the laminar flow of the pulp slurry causes the pulp fibers to separate from the slurry thereby to form pulp balls.

Referring particularly to Figs. 1 and 2, there is illustrated a flow box comprising a bottom wall 10 having vertical side walls 11 and 12 and back and front walls 13 and 14 all projecting upwardly therefrom in the usual manner. The upper front portion of the flow box is partially blocked off by means of a slice or gate 14'. Referring particularly to Fig. 1, the forward portions of the side walls 11 and 12 are each provided with tongues 15 and 16 which function as guides in which the slice 14' is slidably mounted. A screw jack 17 may be attached to the top portion of the slice 14' for the purpose of increasing or decreasing the opening between the lower portion of the slice and an apron board 23 which projects forwardly from wall 14. If desired, the entire flow box may be mounted upon leg members 18, 18 only two of which are disclosed herein.

Extending crosswise within the flow box are a pair of upper baffle plates 19 and 20 each of which is spaced slightly from the base 10 of the box. Between the plates 19 and 20 is provided a third baffle plate 21 which projects upwardly from the base 10 and which terminates at a point below the top of the flow box. The rear wall 13 of the flow box is provided with one or more conduits 22 which function as a means whereby pulp solutions may be admitted into the flow box.

As thus described the present flow box is substantially of a design used for many years in conjunction with Fourdrinier type paper making machines. In the operation of such a Fourdrinier type machine the pulp fibers are mixed in a solution of water and then this fiber and water solution, which is usually called a slurry, is admitted into the flow box by way of the conduit 22. Referring particularly to Fig. 2, it is to be understood that this slurry will find its way through the flow box in a tortuous path as defined by the baffle plates 19, 20, and 21. By means of these baffle plates the slurry is given a thorough mixing before it reaches the forward portion of the flow box. After passing about these baffle plates the slurry is ejected from the flow box in a thin stream the thickness of which is initially determined by the height of the slice 14' above an apron board portion 23 of the wall member 14. After being delivered under the slice 14' the slurry will be deposited upon the usual Fourdrinier wire 24.

Referring particularly to Figs. 1, 2, and 6, the Fourdrinier wire 24 comprises an endless belt which is trained over spaced rolls which are generally designated as a breast roll 25 and a lower couch roll 26. Power is supplied to these rolls so

that the wire 24 will be continuously driven in a direction designated by the arrows 27 thereby to carry the pulp web, designated by the numeral 28, between the lower couch roll 26 and an upper couch roll 29, which latter two rolls are effective to remove a portion of the water from the pulp web 28. After the pulp web passes between the upper and lower couch rolls it is transferred to an endless felt belt 30 which is trained between a plurality of press rolls 31, 31. These rolls are preferably power driven, so that the felt 30 can carry the pulp web through a plurality of pairs of additional oppositely disposed press rolls, not shown, for the purpose of removing more water from the web. After passing through one or more press roll stations the web is trained over a plurality of steam-heated drying cylinders 33, 33, which, by means of heat and pressure, will remove any water which is left in the pulp web.

When the pulp web finally emerges from the steam-heated drying cylinders it is usually calendered by means of oppositely disposed calendering rolls 34, 34, which function to produce a proper finish on the paper surfaces.

As noted above, the above described process of making paper has a glaring defect in that the usual Fourdrinier flow box is not effective to deposit a pulp web upon the wire in a manner such that the web will have the pulp fibers uniformly disposed therein. Referring particularly to Figs. 7 and 8, it is to be understood that as the pulp slurry is admitted into the box through the conduit 22 small vortices of pulp fibers will be formed as at points 35, 35. It has been found that as the slurry is passed through such flow boxes concentrations of pulp fibers will be formed wherever a vortex would normally occur in the solution contained within the box. Furthermore, no matter how the flow box is designed the slurry will be subjected to the characteristic laminar flow effects with the result that those portions of the slurry which are adjacent the sides of the flow box will be slowed down relative to the main current of slurry passing through the box. As these portions of the slurry are slowed down it has been found that the fiber particles of the pulp will accumulate in small balls with the result that a homogeneous distribution of the fibers within the water solution is impossible. Although, in the past, various mechanical means have been provided within the flow box for the purpose of breaking up these pulp concentrations no adequate method has heretofore been devised which will prevent some pulp balls from passing from the flow box and onto the wire. As hereinabove noted, these small concentrated fiber deposits will show up in the paper as defects.

In order to obviate these difficulties the present invention contemplates the provision of means whereby compression waves may be passed through the pulp slurry as the same passes through the flow box. It has been found that by so subjecting the slurry to these compression waves the slurry is rendered substantially free of any pulp concentrations. Apparently these compression waves are effective to break up any concentrations of pulp fibers within the slurry with the result that the fibers are distributed uniformly throughout the water solution. Furthermore, it appears that those fibers which would normally tend to cling to the sides of the flow box and thus concentrate together in the form of balls, are driven away from the flow box sides thus to reenter the moving stream of slurry.

In order to produce these compression waves

within the slurry various means may be applied to the flow box. For example, referring particularly to Figs. 1, 2, 3, and 5, the flow box may have attached to the side wall 11 thereof a plurality of vibratory means each of which will set up vibrations or impulses which may be transferred directly to the fluid contained within the flow box. Such vibratory means may be effective to impart their impulses directly to the side wall 11 which will in turn transfer these impulses directly to the fluid or, if desired, the flow box may be provided with a plurality of diaphragms which may be set in movement by the vibratory means to the end that these diaphragms will impart their impulses directly to the solution. This latter method is particularly illustrated in Figs. 3 and 5 of the present drawings.

A typical form of pneumatic vibrator is illustrated in Fig. 5. In order to apply this pneumatic vibratory device to a flow box the wall portion 11 is formed with a substantially circular aperture 36 over which is secured a circular diaphragm 37. This diaphragm may be welded or otherwise secured to the wall 11 as at points 38 and 39. Mounted directly upon the diaphragm 37 is a pneumatic vibrator comprising a substantially cylindrical housing 40 which is provided with a hollow cylinder 41 therein. A vibratory piston 42 is slidably mounted within the cylinder 41 which is provided with intake ports 43 and 44 and exhaust ports 45 and 46. The intake ports 43 and 44 are connected together as at 47 to a common air hose 48. Provided within the lower portion of the cylinder 41 is a coil compression spring 49 which is adapted to bias the piston 42 upwardly. This pneumatic vibrator is of a usual design and it is adapted to have the piston 42 thereof reciprocate back and forth within the cylinder under the impetus of air which is directed into the cylinder by means of the hose 48. Referring particularly to Fig. 5, it will be understood that as the air is delivered to the hose 48 it will enter both of the intake ports 43 and 44 but since the piston 42 is in its upper position the inlet port 44 will communicate directly with the outlet port 46 with the result that the air in the upper portion of the cylinder will be effective to force the piston downwardly within the cylinder against the action of the spring. It will be clear that when the piston reaches a lower position within the cylinder the exhaust port 46 will be closed by the piston 42 and the exhaust port 45 will be placed in communication with the inlet port 43 so that the air entering the inlet port 44 will be effective to bias the piston upwardly. The spring 49 will, of course, function to prevent the piston from being air-locked in a central position within the cylinder 41. This pneumatic vibrator may be suitably secured as by a rivet 50 to the center portion of the diaphragm 37 and, therefore, it is to be understood that as the piston 42 vibrates back and forth within the cylinder 41 impulses will be set up within the diaphragm 37. Since this diaphragm is exposed to the fluid within the flow box it will be effective to impart compressional waves directly to the fluid contained within the box. The amplitude and frequency of these compressional waves may be varied by adjusting the pressure of the air as the same enters the hose 48. If desired, a valve 51 may be provided in the air-line so that the pressure of the air supplied to the pneumatic vibrator may be readily varied.

In order to protect the pneumatic vibrator from damage either from the presence of liquid or from

mechanical blows, the present unit is provided with a substantially circular ring 52 which is secured directly to the outside portion of the wall 11 by means of a plurality of bolts 53. A substantially cylindrical cap 54 may be removably secured over the ring 52 by means of a plurality of screws 55. Thus, this cap 54 will prevent the pneumatic vibrator from being exposed to any liquid which may spill over the outside of the flow box. Of course, it is to be understood that the herein above described pneumatic vibrator may be attached directly upon the outside wall of the flow box thus obviating entirely the use of a diaphragm member 37. In this latter case, the walls of the flow box will function as diaphragms thereby to transmit the impulses from the pneumatic vibrator directly to the pump slurry.

Figs. 3 and 4 illustrate still another form of vibratory device which is electrically powered and which may be used in conjunction with the present apparatus. To install this second form of vibratory device the side wall 11 may again be provided with a circular aperture 36 which is covered by means of a diaphragm 37. This electrical vibrator comprises a substantially circular ring 56 which is secured directly to the side wall 11 by means of a plurality of bolts 57. Projecting outwardly from the ring 56 are a pair of arms 58 and 59 which are connected together by means of a yoke member 60. Extending across the base portions of the arms 58 and 59 is a member 61 the central portion of which is adapted to have slidably received therein a non-magnetic armature shaft 62 of which one end portion is secured directly to the center of the diaphragm 37 by means of a rivet 63. The other end of this armature shaft has mounted thereon a circular armature 64 which is spaced from a stator member 65 the upper portion of which is mounted directly in non-magnetic core holders 66, 66 which in turn are mounted upon the yoke 60 by means of bolts 67, 67. Surrounding the mid portion of the stator 65 is an energizing coil 68 having the usual lead wires 69 extending therefrom. This entire electrical vibrator is adapted to be enclosed completely by means of a cylindrical cap 54 which may be snapped over the ring 56 and secured thereto by means of a plurality of screws 55.

Referring particularly to Fig. 4, the coil 68 is adapted to be connected by means of wires 69 to an alternating current generator 70 which is driven by variable speed direct current motor 71. A rheostat 72 is provided in the motor leads so that the speed of the motor may be varied to the end that the frequency or cycle of the generator may also be varied. Motor leads 73 extend from the motor to a proper source of electrical energy. Thus, by means of the rheostat 72 the impulse frequency of the armature 64, and consequently that of the diaphragm 37, may be varied at will. Under the impulses set up by the electrical vibrator the diaphragm 37 will be effective to transmit compression waves directly to the pulp slurry. It is also to be understood that this electrical vibrator may have its armature mounted in a manner such that it will transmit its impulses directly to the side wall 11 of the flow box rather than to a diaphragm 37. Referring particularly to Figs. 1 and 2, in one form of the present invention the flow box may be provided with a plurality of vibrating devices designated generally by the numerals 14, 14. These devices 14 may be disposed in a manner such that they will be effective to set up compressional waves between the baffle plates 19, 20 and 21.

As thus disposed, these vibratory devices will propagate compressional waves in a direction substantially transverse to the direction of flow of the pump slurry through the flow box. However, the present invention is not to be limited to this particular disposition of vibratory devices for such vibratory units may be disposed upon the flow box in a manner which best meets the needs of the particular design of the flow box; it being understood that various installations of Fourdrinier paper making machines require various types of flow box designs. It has also been found that if a vibratory device is applied to the apron board portion 23 of the flow box it will be effective to set up compressional waves within the pulp slurry as the same passes beneath the slice 14' and over the forward portion of the apron board. By so subjecting the pulp slurry to these compressional waves at this particular point in its progress, it has been found that the pulp fibers are set into motion to the end that when the slurry is deposited upon the wire 24 these pulp fibers will be homogeneously arranged throughout the pulp web but at the same time a great percentage of the fibers will be disposed with their longitudinal axes vertically arranged as opposed to the usual condition in which most all of the fibers are horizontally disposed. In other words, these compressional waves will set the pulp fibers in motion so that the flow of the pulp slurry onto the wire will not cause all of the fibers to be disposed with their axes in one direction. Thus, by sending compressional waves up through the slurry as it flows onto the wire there is effected a stronger pulp web for the reason that the fibers of the pulp will be interlaced in all directions.

Fig. 1 illustrates one form of the present invention in which the various vibratory devices 14, 14' are energized from either a single electrical or pneumatic source of energy by way of the main conduits 75, 75' and the distributing conduits 76, 76'. It is to be understood that such vibratory devices may also be associated with the flow box side wall 12 or bottom 10 thereby to provide such devices on each side of the box. However, as shown in Fig. 1, the vibratory devices are associated with the wall 11 only, and in such an installation it has been found that the compression waves will be sent out from the wall 11 to pass through the slurry and strike against the opposite wall 12 which will deflect the waves and reverse the direction thereof. Thus the entire con-

tents of the flow box will be agitated by the passage of compression waves therethrough. It is to be understood that, in effect, the opposite side walls 11 and 12 of the flow box function as diaphragms between which the compression waves travel with the result that all of the pulp fibers are subjected to the agitating action of these waves.

Pneumatic oscillatory units such as disclosed in Fig. 5 of the drawings are best capable of producing from about 500 to 6000 vibrations a minute whereas the electrical oscillatory unit disclosed in Fig. 3 is best capable of producing from 6000 to over 12,000 vibrations a minute.

I claim:

In a paper making machine, the combination of a travelling forming wire, a flow box having horizontal walls and upstanding walls over and between which a stream of pulp and water slurry is adapted to be passed, means disposed at one end of said flow box for receiving a stream of the slurry, means disposed at the other end of said flow box for depositing a thin stream of the slurry upon said forming wire, a plurality of relatively thin diaphragms connected to said horizontal and upstanding walls as constituent parts thereof, said diaphragms being thereby exposed to the slurry stream passing through said box and said diaphragms being spaced apart along said box's length in the direction of slurry stream flow, and means for imparting high frequency vibrations to each diaphragm so as to propagate compression waves back and forth within the slurry as it passes through said flow box and in a direction transverse to the direction of slurry flow thereby to effect a homogeneous suspension of the pulp fibers throughout the slurry.
